UNITED STATES PATENT OFFICE.

JOSEPH SYLVAN, OF CHICAGO, ILLINOIS.

VENTILATOR.

1,306,866.

Specification of Letters Patent. Patented June 17, 1919.

Application filed March 15, 1919. Serial No. 282,939.

To all whom it may concern:

Be it known that I, JOSEPH SYLVAN, a citizen of the United States, and a resident of Chicago, county of Cook, and State of Illinois, have invented certain new and useful Improvements in Ventilators; and I do hereby declare that the following is a full, clear, and exact description thereof, reference being had to the accompanying drawings, and to the letters of reference marked thereon, which form a part of this specification.

This invention relates to improvements for ventilators and consists of the matters hereinafter described and more particularly pointed out in the appended claims.

The object of the invention is to provide an improved ventilator for a vehicle and is shown herein as applied to a railway car.

The improved ventilator is of novel and simple construction, is cheap to manufacture and is efficient to withdraw and discharge the foul air from the vehicle, and at the same time to prevent rain or snow from entering the vehicle through the ventilators.

As has been stated, the ventilator is shown herein as applied to a railway car and in such use two ventilators are required, one at each end of the car, one being in use when the car is moving in one direction, and the other being in use when the car is moving in the opposite direction,—the one in use being the one at the rear of the moving car.

In the drawings:

Figure 1 represents a view in side elevation of the rear end of a railway car or coach with the improved ventilator applied thereto.

Fig. 2 represents a view in rear end elevation of the same.

Fig. 3 is a view representing, on an enlarged scale, a section through the ventilator in a plane indicated by the line 3—3 of Fig. 2.

Referring now in detail to that embodiment of the invention illustrated in the accompanying drawings:—10 indicates the ventilator as a whole, which is made of sheet metal, the same being attached to the top or roof 11 of the car, and communicating with the interior thereof by means of an opening 12 formed in said roof (see Fig. 3).

The ventilator is made of substantial width, extending a considerable distance to either side of the longitudinal median line of the roof of the car. It is provided with a base flange 13 which bears upon the roof of

the car, and screws passing through said flange securely attach the ventilator as a whole to said roof (see Fig. 3). The base is curved transversely or otherwise formed, 60 as indicated at 14 in Fig. 2, to fit the roof of the car when said roof is curved as in this instance.

The ventilator has side or end walls 15, 15 which rise from the base and are spaced 65 apart to define the entire width of the ventilator. 16 indicates the rear wall of the ventilator. Said wall is inclined forwardly and upwardly, and has a slight curvature 17 at its top, toward the rear. Said wall consists 70 of a sheet metal plate 16^x bent back upon itself to form the upright part of the wall, including the curved top part 17, and the rearwardly and forwardly projecting bottom extensions 18 and 19 respectively. The 75 extension part 18 provides a part of the base flange 13 at the rear of the ventilator. The extension part 19 is inclined forwardly and upwardly only slightly from the horizontal, for a distance about half the length 80 of the ventilator and is then carried vertically upward and forward in substantial parallel relation with the rear wall 16 to provide a splash flange 20, the top of which terminates in a rearwardly and downwardly 85 curved flange or lip 21. The plate 16^x forming the parts above described, extends the full width of the ventilator and is secured at its ends to the side or end walls 15, 15 by solder or in any other convenient manner 90 known in the sheet metal art.

22 indicates the front wall of the ventilator. This wall is made of a sheet metal plate 22^x extending the width of the ventilator and has a part bent forwardly and upwardly 95 in parallel relation to the rear wall 16 and flange 20 before mentioned, to provide the front wall 22 proper; a second part 23 bent horizontally forward from the bottom edge of the wall 22 to provide a portion of the 100 base flange 13 of the ventilator; a third part 24 which is bent forwardly and downwardly from the top edge of the wall 22 to provide a depending lip at said top edge; and a fourth part 25 curved rearwardly from the top edge 105 of the wall 22, to provide a deflector plate which covers a passageway or flue 26, between the splash flange 20 and the front wall 22 that communicates with the opening 12 in the car roof 11. The rear end of the deflector plate 25 overhangs the flange 20 and depends into the space between the lip of

said splash flange and the rear wall 16, thus providing a staggered continuation 26^a of said passageway or flue 26. The plate forming the parts just described, as in the case 5 of the other plate, has its ends secured in any suitable manner to the side walls 15, 15 of the ventilator. 27 indicates the top or cover of the ventilator. Said cover is curved forwardly and downwardly in substantial 10 parallelism with the deflector plate 25 and depends at its front end somewhat below the lip 24. The rear end of the cover is curved upwardly and rearwardly as indicated at 28, thus forming with the top curved part 17 of 15 the rear wall, a mouth or discharge opening 29. From an examination of Fig. 3, it will be seen that this cover 27, together with the deflector plate 25 and lip 24, provides a passageway 30 leading from the space in front 20 of the front wall 22 of the ventilator to the discharge opening 29. The cover plate, as in the case of the other plates, is attached to the side walls of the casing.

The operation of the ventilator is as follows:

As the car or vehicle moves forwardly, as indicated by the large arrow 31 in Fig. 1, a current of air will be produced in the direction of the arrows over the top of the 30 ventilator, as shown in Fig. 3, and at the sides thereof. This will induce a suction within the mouth 29 of the ventilator which will act to draw the air through the flue 26 and its continuation 26^a, up about the rear 35 end of the deflector plate 25 and then out through the mouth 29 of the ventilator. This suction will be greater as the speed of the car is increased.

Any rain or snow that may fall into the 40 mouth or discharge opening 29 of the ventilator, which, as is illustrated, is directed somewhat upwardly, will fall directly into a precipitation chamber 19^a, defined by the side walls 15, the rear wall 16, splash flange 45 20 and bottom wall 19, or upon the deflector plate 25, which latter being curved, will discharge it into said chamber 19^a. As has been pointed out, the bottom wall 19 is slightly inclined upwardly so that this water will 50 gravitate toward the rear end of the chamber 19^a and in order to drain this chamber, I provide discharge openings 32 in the side walls of the casing, in the angle between the rear wall and the bottom wall.

Such air currents as strike the front wall 22 of the ventilator will be deflected upwardly and then downwardly by said front wall and by the depending lip 24, and will 55 not enter the ventilator, but will be deflected outwardly to be discharged at the sides of the ventilator.

When the car is going in the opposite direction with respect to one of the ventilators, that is to say, so that currents of 60 air will enter at the mouth 29 of the venti-

lator, as indicated by the dotted line arrows in Fig. 3, said currents will simply pass in the direction of said dotted arrows through the channel 30 and will escape at the bottom end 30^a of said channel without the ventilator, being deflected into this path by means of the deflector plate 25.

While in describing my invention, I have referred to the same as being used in connection with a railway car, I do not wish to be limited thereto, as the same may be used to advantage upon limousine automobiles and other vehicles.

I claim as my invention:

1. A ventilator consisting of a casing having upright side, front and rear walls, and a top wall, said top and rear walls being formed to present an outlet opening which is faced upwardly and rearwardly, an intermediate wall between said front and rear walls defining with said front wall a flue, which opens through the bottom of the casing, and a deflector plate located above said flue, said deflector plate together with said rear wall defining a staggered passageway 80 connecting said flue with said outlet, and said deflector plate with said top wall defining a second passageway leading from the space in front of said front wall, to said outlet opening.

2. A ventilator consisting of a casing having upright side, front and rear walls, and a top wall, said front and rear walls being inclined forwardly, and said top and rear walls being formed to present an outlet opening which is faced upwardly and rearwardly, an intermediate wall between said front and rear walls defining with said front wall a flue, which opens through the bottom of the casing, a bottom wall connecting the 100 bottom ends of said rear and intermediate walls, said rear, bottom and intermediate walls defining a precipitation chamber which drains through openings in the side walls, a deflector plate overhanging said flue and 110 defining with said rear wall, a staggered passageway connecting said flue with said outlet, and said deflector plate with said top wall defining a second passageway leading from the space in front of said front wall, 115 to said outlet opening.

3. A ventilator consisting of a casing having upright side, front and rear walls, and a top wall, said front and rear walls being inclined forwardly and said top and rear walls being formed to present an outlet opening which is faced upwardly and rearwardly, an intermediate wall between said front and rear walls, defining with said front wall a flue, which opens through the 120 bottom of the casing, said intermediate wall having a rearwardly curved lip at its top edge, a bottom wall connecting the bottom ends of said rear and intermediate walls, said rear, bottom and intermediate walls defining a second passageway leading from the space in front of said front wall, 125 to said outlet opening.

65

- fining a precipitation chamber which drains through openings in the side walls, a deflector plate overhanging the intermediate wall and defining with said rear walls, a 5 staggered passageway connecting said flue with said outlet opening, and said deflector plate with said top wall defining a second passageway leading from the space in front of said front wall, to said outlet opening.
- 10 4. A ventilator consisting of a casing having upright side, front and rear walls, and a top wall, said front and rear walls being inclined forwardly, and said top and rear walls being formed to present an outlet 15 opening which is faced upwardly and rearwardly, an intermediate wall between said front and rear walls defining with said front wall a flue, which opens through the bottom of the casing, said intermediate wall having a rearwardly curved lip at its top 20 edge, a bottom wall connecting the bottom ends of said rear and intermediate walls,

said rear, bottom and intermediate walls defining a precipitation chamber which drains through openings in the side walls, 25 a deflector plate extending forwardly and downwardly from the top edge of the front wall to form a lip, and extending rearwardly so as to overhang said intermediate wall and defining with said rear wall, a 30 staggered passageway connecting said flue with said outlet opening, and said deflector plate with said top wall, defining a second passageway leading from the space in front of said front wall, to said outlet opening. 35

In testimony that I claim the foregoing as my invention, I affix my signature in the presence of two witnesses, this 11th day of March, A. D. 1919.

JOSEPH SYLVAN.
